PAPER CUTTING MACHINE

Frederick D. McLaughlin, Shaker Heights, Ohio,
assignor to The Chandler & Price Company,
Cleveland, Ohio, a corporation of Ohio

Application December 13, 1949, Serial No. 132,758

4 Claims. (Cl. 164—52)

1

This invention relates as indicated to paper cutting machines and, more particularly, to novel knife control means therefor.

The usual paper cutting machine comprises a table provided with back and side gauges for properly positioning a stack of sheets thereon, a binder clamp operative firmly to clamp such stack upon the table, and a generally vertically reciprocable knife adapted to be brought down upon the stack thus clamped to trim the latter. The present invention is concerned only with means for effecting proper control of the knife bar and knife during making of the cut. For a detailed description and explanation of certain preferred mechanism for operating the binder clamp and knife, reference may be had to the following co-pending applications of William C. Rupp, namely, application Serial No. 60,341, "Paper Cutting Machine," filed November 16, 1948; application Serial No. 112,659, "Brake Mechanism for Paper Cutting Machines and the Like," filed August 27, 1949; and application Serial No. 123,865, "Knife Control for Paper Cutting Machine," filed October 27, 1949.

In substantially all paper cutting machines where the table is at all wide, there is a definite tendency on the part of the knife and knife bar to bend or bow rearwardly in their center portions due to the bevel of the knife when such knife is making the cut. This tendency is less when cutting enameled stock but the deflection is sometimes as much as .015 inch when cutting sulphide bond with a 37-inch knife. This deflection could, of course, be reduced by employing a still more massive knife bar but such modification is undesirable for several reasons such as increase in material costs, an increase in the power necessary for rapid reciprocation of the knife bar and knife and obstruction of the lighting means which it has been found to be very desirable to provide in the upper housing of the machine to illuminate the stack where engaged by the binder clamp. In consequence, it has been usual merely to ignore such deflection and resultant inaccuracy of the cut since the same is not sufficient to be material for many purposes. In a number of instances, however, extreme accuracy is desired and machines now on the market are not found satisfactory.

It is accordingly a primary object of my invention to provide a paper cutting machine including means insuring the obtaining of an extremely accurate cut.

Another object is to provide knife control means effective to prevent rearward bowing or

2

deflection of the knife bar and knife during the cut.

Still another object is to provide means supporting the knife and knife bar against rearward deflection whereby the employment of a relatively light knife bar is made feasible, thus facilitating rapid reciprocation of the same and avoiding interference with illumination of the stack by lighting means within the upper housing of the machine.

Other objects of my invention will appear as the description proceeds.

To the accomplishment of the foregoing and related ends, said invention then comprises the features hereinafter fully described and particularly pointed out in the claims, the following description and the annexed drawing setting forth in detail certain illustrative embodiments of the invention, these being indicative, however, of but a few of the various ways in which the principle of the invention may be employed.

In said annexed drawing:

Fig. 1 is a front elevational perspective view of a typical paper cutting machine embodying my invention;

Fig. 2 is a front elevational view of a modified binder clamp which I employ in association with the knife bar of my machine;

Fig. 3 is a top plan view of such binder clamp;

Fig. 4 is a vertical sectional view taken along the line 4—4 on Fig. 2; and

Fig. 5 is a vertical sectional view transversely through such binder clamp and knife bar showing the manner in which the same cooperate to achieve the objectives of my invention.

Referring now more specifically to such drawing and especially Fig. 1 thereof, the paper cutting machine there illustrated is of generally conventional construction comprising a base frame 1 carrying a bed or table 2 upon which a stack of sheets may be positioned to be cut. A back gauge 3 may be adjusted forwardly or rearwardly of table 2 by means of hand wheel 4, the position of such gauge being indicated by a traveling steel tape in window 5 as described in Reichart et al. Patent No. 2,203,547. A knife bar 6 carrying knife 7 is mounted for generally vertical reciprocation in upper frame 8, a wooden knife stick 9 being inset in the upper surface of the table to avoid possible damage to the knife.

The knife bar 6 and knife 7 are adapted thus to be reciprocated by means of a connecting rod 10, crank 11, and crankshaft 12 driven through a clutch from a flywheel driven by an electric motor (not shown). Such clutch

for engaging and disengaging the flywheel is adapted to be actuated by a hand lever 13, preferably of the safety type such as that requiring the same to be first moved to the right and then to the left as viewed in Fig. 1 to cause engagement of the clutch to reciprocate the knife bar. When one cycle of operation has been completed, the clutch will be automatically kicked out and the brake (also not shown) applied, leaving the knife in elevated position.

Back gauge 3 may be shifted back and forth as desired by means of hand wheel 4 and locked in adjusted position by locking lever 14.

Referring now also to Figs. 2-5 inclusive, a binder clamp 15 is mounted for vertical reciprocation directly behind knife bar 6, such clamp being provided with extensions 16 and 17 fitting in ways in upper frame 8. A presser foot 18 on the lower end of clamp 15 is adapted to engage a stack of sheets 19 upon table 2. The front face of the clamp is relieved, except for a region adjacent such foot and except for a bearing surface described below. The knife 7 and knife bar 6 are thus slightly spaced from the front face of the binder clamp except along the foot of the latter. The clamp may be provided with a plurality of rearwardly extending resilient fingers 20 which bear upon the upper surface of the stack.

Binder clamp 15 is carried by a vertically extending screw 21 threadedly engaging nut 22 which is locked against rotation about a vertical axis in such clamp and has any lateral play taken up by means of set screw 23. A collar 24 carried by spindle 25 constituting an upper extension of screw 21 is adapted to engage the upper surface of bearing 26 to limit downward movement of such spindle, and a lower collar 27 similarly limits upward movement of the spindle. Upon driving shaft 28 and screw 21 by means of gearing 28, 29 (see Rupp application Serial No. 123,865 above referred to), the binder clamp will be caused to travel upwardly or downwardly depending upon the direction of rotation of such screw. Gearing 28, 29 may desirably be driven by means of an electric motor 30 carried by upper housing 8.

An electric light such as fluorescent tube 31 may desirably be provided within forwardly extending shield 32 to illuminate the upper surface of stack 19 in the region engaged by the binder clamp presser foot.

While as above indicated the front face of binder clamp 15 is for the most part relieved except adjacent the lower edge thereof, a vertically extending bearing surface 33 of substantial width is also provided adjacent the central portion of the front face of such clamp. Such surface is flat and lies in the same plane as the narrow unrelieved base portion 34. As best shown in Fig. 1, the front portion of surface 33 is offset to the right, such surface being shaped and proportioned to insure that a limited co-acting bearing surface on the knife bar will continue to engage the same throughout the downward stroke of the latter, such knife bar ordinarily being slightly shifted longitudinally from right to left during the making of the cut to afford a slicing action.

Knife bar 6 is drilled and tapped at 35 communicating with a slightly larger diameter opening in the rear face of the knife bar adapted to receive the head 36 of a screw 37 inserted therein (see Fig. 5). The head of the screw is dimensioned to be received entirely within such larger diameter opening in the knife bar but may protrude therefrom upon adjustment of the screw, 75

the latter being locked in adjusted position by means of set screw 38.

The operation of my new mechanism may now be understood as follows. Screw 37 will be turned to bring head 36 into engagement with bearing surface 33 on binder clamp 15, sufficient pressure being exerted on the latter to insure that the binder clamp is in contact with its rearward ways. There is consequently no possibility of play between the knife bar and clamp, and the latter will rigidly support the former against any tendency toward rearward bowing of its center portion. The stack of sheets is next properly positioned upon table 2 and presser foot 18 brought down into clamping engagement therewith. This is accomplished by rocking hand lever 13 to the right as shown in Fig. 1 to operate micro-switch 39, thereby completing a circuit energizing electric motor 30 to drive spindle 25. When the stack has been thus clamped, the operator may now move the hand lever to the left to engage the clutch of the knife drive mechanism and disengage the brake, driving crankshaft 12 to reciprocate connecting rod 10 and thereby reciprocate knife bar 6 and knife 7 to make the cut. Upon completion of this cycle, lever 13 is automatically rocked in a clockwise direction back into starting position as shown in Fig. 1 and the knife drive clutch disengaged and the brake reapplied. 30 When the binder clamp has been returned to its fully elevated position, it will engage limit switch 40, stopping motor 30. As above indicated, the mechanism for thus reciprocating the binder clamp and knife forms no part of the present invention.

When knife 7 enters upon its cut, the bevel of the knife tends to deflect the knife and knife bar rearwardly in their central portions, thus slightly bowing the same and resulting in an inaccurate cut. Engagement of properly adjusted screw head 36 with bearing surface 33, however, serves effectively to prevent any such action, and a remarkably accurate cut is instead achieved.

The bevel of the knife edge is, of course, always on the side away from the binder clamp and therefore always tends to cause bowing of the knife and knife bar toward such clamp. Deflection is particularly apparent when a very wide stack is being cut. By means of my adjusting screw I am enabled to ensure an accurate cut despite variations in material, wear of the bearing surfaces, and possible initial looseness of the mounting of the binder clamp in its ways. The transverse rigidity of the binder clamp is thus utilized to provide lateral support to the knife bar on the side where needed, during reciprocation of such bar.

Other modes of applying the principle of the invention may be employed, change being made as regards the details described, provided the features stated in any of the following claims or the equivalent of such be employed.

I therefore particularly point out and distinctly claim as my invention:

1. In a paper cutting machine having a table adapted to support a stack of sheets thereon, a vertically reciprocable clamp adapted to clamp such stack on such table, and a knife adapted to be brought down adjacent such clamp to cut such stack; a knife bar supporting such knife and secured thereto, such knife having a cutting edge beveled on the side away from such clamp whereby a tendency to transverse deflection arises during making of a cut, a flat vertical bearing surface on the side of such clamp disposed ad-

5 jacent and parallel to said knife bar and such knife, said bar having an opening therethrough opposed to said surface, a flat-headed screw threadedly engaged in such opening with such head opposed to and adapted to be brought into engagement with said surface, and a set screw adapted to lock said flat-headed screw in adjusted position, said surface being dimensioned to engage said flat-headed screw during the cutting stroke of such knife to reinforce the latter and said bar against deflection.

2. In a paper cutting machine having a table adapted to support a stack of sheets thereon, a vertically reciprocable clamp adapted to clamp such stack on such table, and a knife adapted to be brought down adjacent such clamp to cut such stack; a knife bar supporting such knife and secured thereto, such knife having a cutting edge beveled on the side away from such clamp whereby a tendency to transverse deflection arises during making of a cut, such clamp having a face toward said bar and such knife relieved except for a narrow band along the foot thereof and a region adjacent the central portion of such face, such region comprising a flat bearing surface lying in the same plane with such band parallel to such knife and said bar, said bar having an opening therethrough opposite such flat surface on such clamp, a flat-ended screw threadedly engaged in such opening with such end opposed to and adapted firmly to engage such flat surface, and means operative to lock said screw in adjusted position, such flat surface being dimensioned to engage said flat-ended screw during the cutting stroke of such knife to reinforce the latter and said bar against deflection.

3. In a paper cutting machine having a table adapted to support a stack of sheets thereon, a vertically reciprocable clamp adapted to clamp such stack on such table, such clamp being transversely rigid and a knife adapted to be brought down adjacent such clamp to cut such stack; a knife bar supporting such knife and

secured thereto, such knife having a cutting edge beveled on the side from such clamp whereby a tendency to transverse deflection arises during making of a cut, such clamp having a flat vertical bearing surface disposed toward and parallel to said knife bar and knife, a member carried by the central portion of said knife bar for adjustment relative to said bar toward and away from such adjacent clamp and adapted to be brought into engagement with a small portion of such flat vertical surface on such clamp, and means operative to lock said member in adjusted position rigid with said bar, such flat surface being dimensioned slidingly to engage such member during the cutting stroke of such knife to reinforce the latter and said bar against deflection.

4. In paper cutting machines and the like having a table adapted to support a stack of sheets thereon, a vertically reciprocable transversely rigid clamp adapted to clamp such stack on such table, and a separately actuated knife adapted to be brought down adjacent such clamp to cut such stack; a knife bar supporting such knife and secured thereto, such knife having a cutting edge beveled on the side away from such clamp whereby a tendency to transverse deflection arises during making of a cut, and a member interposed between the opposed sides of said clamp and knife bar in a local region generally midway between the ends of the same, said member being mounted for adjustment forcibly to urge said clamp and bar apart in such local region during making of the cut.
